To all whom it may concern:

Be it known that I, H. C. WILCOX, of West Meriden, in the county of New Haven, and State of Connecticut, have invented or produced an original Design for a Casket-Handle; and

To enable others skilled in the art to make and use the same, I will proceed to describe, referring to the drawings or photographic views, in which the same letters indicate like parts in each of the figures.

In the accompanying views—
a are fastening-plates of ornamental shape and configuration.

They are all combined, substantially as shown and set forth, to produce a rich and highly-ornamental design for a casket-handle.
